UNITED STATES PATENT OFFICE

157,845

AUTOMOBILE AIR DEFLECTOR

Oscar W. Dorfman and Ernest Peters, Chicago, Ill.

Application April 12, 1949, Serial No. 1,922

Term of patent 7 years

(Cl. D14—6)

To all whom it may concern:

Be it known that we, Oscar W. Dorfman and Ernest Peters, both citizens of the United States and residents of Chicago, Cook County, Illinois, have jointly invented a new, original, and ornamental Design for an Automobile Air Deflector, of which the following is a specification, reference being had to the accompanying drawing, forming a part thereof.

Fig. 1 is a perspective view, on a reduced scale, of an automobile air deflector, showing our new design.

Fig. 2 is a substantially full scale front view of the same.

Fig. 3 is a top plan view of the same.

Fig. 4 is a rear elevational view of the same.

Fig. 5 is a right end elevational view of the same, looking at Fig. 2 but rotated clockwise 90°.

Fig. 6 is a fragmentary sectional view of the same, taken as indicated by the line 6—6 in Fig. 2.

Fig. 7 is a sectional view of the same, taken as indicated by the line 7—7 in Fig. 2.

Fig. 8 is a fragmentary sectional view of the same, taken as indicated by the line 8—8 in Fig. 2.

We claim:

The ornamental design for an automobile air deflector, substantially as shown.

OSCAR W. DORFMAN.

ERNEST PETERS.
